UNITED STATES PATENT OFFICE.

ORVILLE H. ENSIGN, OF MADISON, WISCONSIN.

GAS-GENERATOR.

1,079,118.

Specification of Letters Patent. Patented Nov. 18, 1913.

Application filed April 30, 1908. Serial No. 430,224.

To all whom it may concern:

Be it known that I, ORVILLE H. ENSIGN, a citizen of the United States, residing at Madison, in the county of Dane and State 5 of Wisconsin, have invented a certain new and Improved Gas-Generator, of which the following is a full, clear, concise, and exact description, reference being had to the accompanying drawings, forming a part of 10 this specification.

My invention relates to that class of gas generators or producers in which a fuel, preferably in liquid form, is fed into a chamber adapted to withstand high temperatures and there partially consumed and dissociated through the agency of an air blast, the air supplied by such blast being insufficient, however, to produce a complete combustion of the fuel. The partial combustion 15 produces a high temperature which serves to dissociate the remainder of the fuel and turn the same into gaseous form, which gases may be drawn from the dissociating chamber and used as desired.

In my invention I prefer to employ liquid fuel rich in hydrocarbons, such fuel, for instance, as petroleum oil. I have found that in former generators for producing gas in this way a large amount of coke was produced, and it is an object of my invention to eliminate this undesirable feature by supplying steam to the gases in the dissociating chamber at such a point as not to interfere with the partial combustion and thus lower 20 the temperature of the chamber, but rather when the gases have become dissociated and it is desired to cool them and combine them into a fixed stable form. I have found that the steam thus introduced is acted upon by 25 the very hot gases and is broken up and in this broken-up condition readily combines with a large part of the coke and incandescent carbon particles with the result that the gas produced is greatly enriched, little 30 if any coke is formed in the dissociating chamber and the carbon remaining in the fixed gas is practically all in the form of lamp black, which may readily be separated from the gas by well known processes.

50 My invention also consists in improved means for regulating the flow of oil to the dissociating chamber in proportion to the amount of gas drawn off from the generator. This regulating means is so designed as to

maintain practically constant the relation 55 of the oil and air supplied to the dissociating chamber for all demands upon the generator, as a result of which the quality of the gas produced is maintained practically constant.

Another object of my invention is to facilitate the uniform supply of oil to the dissociating chamber for any given demand upon the generator by maintaining practically constant the temperature and thus the 65 viscosity of the oil.

In my invention I make use of a restricted opening or orifice in the main used to supply the air to the dissociating chamber, as a result of which different pressures are produced, which are made use of directly to control the supply of oil to the dissociating chamber by the use of two associated oil receptacles, one of which is in communication with the dissociating chamber in such 70 a manner that the oil therein is subjected to the pressure of the chamber while the other receptacle is subjected to the pressure of the air main on the opposite side of the orifice. Oil is permitted to flow from one 75 receptacle to the other by a suitable passageway or conduit, and hence when the pressure in the dissociating chamber is less than the pressure in the air main, which is always the case when the gas is taken from 80 the generator, the difference in the pressures in the oil receptacles may be taken advantage of to supply oil in proper amounts to the dissociating chamber.

Another object of my invention is to automatically regulate the amount of air supplied to the dissociating chamber in proportion to the amount of gas taken from the generator.

The several drawings illustrating my invention are as follows:

Figure 1 is a diagrammatic view of my generator and parts associated therewith necessary to constitute a complete gas-producing plant; Fig. 2 is a sectional view of 100 the generator proper; Fig. 3 is a view of the front of the generator proper taken from the left as seen in Fig. 2; Fig. 4 is a view of the side of the generator away from the observer in the view shown in Fig. 2; Figs. 105 5 to 9, inclusive, show in detail thermostatic means for maintaining practically constant the temperature and viscosity of the oil used

as fuel; Fig. 10 is a detail view of the adjustable orifice in the air main; Fig. 11 shows a modified form of inclined plane for use in the generator.

5 Similar numerals refer to similar parts throughout the several views.

Referring to Fig. 2, the generator proper consists in a chamber 1, formed preferably of cast iron and lined with a fire-resisting material 2, as firebrick or fire clay or similar material of high heat-resisting qualities, and communicating with this chamber 1 by an orifice 8 is a receptacle for the oil to be supplied to the chamber and partly burned therein. This first receptacle communicates by a passageway or conduit 13 through an adjusting valve 14 with a second receptacle 10, into which the oil is led by a pipe 4 and in which the level of the oil is maintained practically constant by weir edge 9, the level of the oil being maintained normally at such a height as to flow over this weir edge and into the outlet pipe 18, from which it returns to a proper tank, in the manner to be explained. Immediately below the orifice 8, inside of the chamber 1, is located an inclined plane 6, down which the oil entering by the orifice 8 may flow. Below the lower end of the inclined plane 6 is located a cup-shaped casting 90, between which and the inclined plane air is caused to flow from the supply pipe or main 3 through the orifice 5 and into the chamber 1. The orifice 5 is located in the air main 3 just before the main 30 discharges into the part of the chamber 1 under the inclined plane 6. A connecting pipe 11 is used to connect the air main 3 below the orifice 5 to the inside of the inclosed receptacle 10. In the upper portion 40 of the chamber 1 is located a hollow casting 65, connected by the pipes 67 and 67^a through the top of such chamber with the tank or drum 66. The casting 65 during the operation of the generator constitutes a 45 heater for converting water contained therein into steam and the drum 66 serves to contain the supply of water required and to also constitute a steam drum for holding the steam produced by the heater 65. Steam 50 from this drum 66 is conveyed to the inside of the chamber by means of pipe 91; such pipe communicating through the valve 74 with pipe 72 located in the rear portion of the chamber 1. This pipe 72 is provided 55 with a series of openings 73, from which the steam is discharged in jets in a direction toward the outlet of the chamber and against the rear wall thereof. The drum 66 is supplied with water through the pipe 29^a and is 60 automatically controlled by the valve 69, operated by the float 68. The steam drum 66 is provided with pressure gage 70, safety valve 71 and water gage 93, for purposes well known.

65 The generator proper is suitably supported

by posts 92 and 93 and is provided with an outlet connecting with the vertical stack or flue 94, which is also lined with firebrick 2 or similar material and which terminates in a return bend 95 of comparatively large 70 radius, from which the gas passes to a second pipe or flue 96 downward as shown in Fig. 1 to a water seal 60, from whence it passes to the washing tank 62 and from such washing tank into a gas holder 55 from 75 which it is supplied by means of the pipe 54 through valve 59 for any purpose desired. The water seal 60 is provided with an overflow seal 61 to take care of any excess water delivered to the water seal 60. The return bend 95 has connected to its middle portion a vertical pipe 63 extending upward and terminating in a relief valve 64 for a purpose to be explained.

As shown in Fig. 1, the oil supply pipe 4 85 connects through valve 97 with a supply tank 23 which is filled with oil by means of a pump 22 from the oil tank 20 through pipe 99, such pump 22 being operated by means of a jack shaft 50 driven by an engine 51 90 operated by gas produced from the generator. The tank 23 is provided with a suitable overflow pipe 100 leading back to the main oil tank 20. The overflow from pipe 18 passes through the trap 19 and thence by 95 means of the pipe 21 to the main oil tank 20. The jack shaft 50 also operates an air blower 49, by which air pressure is produced in the main 3. A relief valve 52, adapted to be operated by a lever 58, is associated with the blower 49, as a result of which any excess of pressure produced by the blower opens the valve and as a result a uniform pressure is maintained in the main 3, the amount of this pressure being determined by the weight 100 53 on the lever 58. The gas holder 55 is adapted to engage lever 56 when such holder is in its upper position, and as a result of such engagement serves to open the relief valve 52 by means of the cord 57 connected 110 between the lever 56 and the lever 58.

The operation of the generator is as follows: In starting the generator the valve 64 is opened and then a priming charge of oil is admitted from cup 101 by means of valve 115 102 into the chamber 1 above the upper end of the inclined plane 6, and as this oil flows down the inclined plane it is ignited by the insertion into the chamber 1 of a piece of lighted waste or some equivalent material 120 through the opening 84 in the side of the chamber 1 near the lower end of the inclined plane 6. The opening 84 is normally closed by means of a gate, as indicated in Fig. 4. At the same time that the priming charge is 125 ignited, air is admitted in small quantities from the air main 3, and as a result combustion is produced, and the products of the combustion or partial combustion in the chamber 1 and the flue 94 slowly pass out 130

through the relief valve 64. The flow of air through the orifice 5 cannot take place without a difference of pressure between the air-supply main 3 and the chamber 1, and therefore the pressure on the surface of the oil in receptacle 103 is reduced below that of the pressure communicated from the air main 3 through the pipe 11 to the surface of oil in the receptacle 10. The oil is thus caused to flow through the valve 14, which is at this time opened by means of the handle 16 being moved to a horizontal position, and the level of the oil in the receptacle 103 is raised until it overflows the outlet edge and passes through the outlet opening 8 and down the inclined plane 6. During the starting of the generator it is advisable to govern both the air and oil supply manually until the generator has warmed up sufficiently to properly produce the gas automatically. This may be done by adjusting the size of the orifice 5 in a manner to be explained and by means of valve 102, thereby regulating the supply of air and liquid fuel. The amount of oil supplied to the inclined plane 6 is regulated by means of the valve 14 by adjusting nut 15 until this quantity of oil bears such a relation to the amount of air supplied from the main 3 through the orifice 5 that only a portion of the oil is consumed and the remainder, consisting largely in the thicker, heavier portions of the oil, flows down the inclined plane 6, and that part of it reaching the lower edge of such plane is blown by the air entering between the inclined plane and the casting 90 up through the flame and toward the outlet opening. If for any reason there is an excess of oil above what is required to produce gas of the proper proportion, it is caught by the cup formed in the upper portion of the casting 90 so located that the air passage into the chamber 1 remains practically the same, whether oil collects in the cup or not. If an excessive amount of oil flows into the cup in the casting 90 it overflows into a second cup 79 from which it is drained off at intervals through the pipe 104 by means of valve 80.

The air entering the chamber 1 is first directed upward and under the inclined plane 6 and finally through the opening 7 into the main portion of the chamber 1, the result of this being that the inclined plane 6 is kept comparatively cool and the oil running down such plane does not carbonize thereon and the inclined plane is kept clean. The casting 90 is prevented from having the oil on its upper surface carbonized by a water jacket formed therein supplied with running water through pipes 78 and 78^a, in a manner well understood.

The action of the heat upon the oil as it flows down the inclined plane is that the lighter and more volatile portions of the oil

are vaporized by the heat almost immediately after the oil enters the chamber 1, and in this vapor condition they readily unite with the oxygen of the air entering the chamber and in this way produce the heat required to vaporize and dissociate the remaining portions of the oil. The amount of oxygen admitted from the air main 3 is not sufficient, however, to completely oxidize all of the oil, and the portions of the oil remaining unconsumed are heated by the combustion in the chamber 1 into incandescent condition and the particles of carbon remaining uncombined are carried in this incandescent condition, together with the products of combustion, to the rear and upward in the chamber 1 and directed gradually, without abrupt change of direction, into the vertical stack or flue 94, in which flue the process of cooling, combining and fixing begins, which continues throughout the flue, the return bend 95 and the pipe 96, as a result of which when the gas reaches the seal 60 it is in stable condition and all that is required is to separate from it the lamp black or free carbon still contained in it. When the gas enters flue 94 it contains a considerable quantity of free oil in volatilized condition, which oil is gradually mixed and changed in condition as it passes through the flue 94 and pipe 96 until after being sufficiently cooled as a result of the intimate association with the other products of the combustion its nature is changed and a fixed gas is the result. It has been found that the oil drops collecting from time to time upon the lower edge of the inclined plane 6 as carried through the burning gases by the air blast are consumed in part, leaving small pellets of coke as a residue, which rapidly collect on the rear wall of the chamber 1 unless means are taken to prevent.

In my invention I introduce a steam jet at such a point as to mingle with the gases after dissociation, and I find that this jet of steam attacks the coke that would otherwise be deposited, and, owing to the highly heated condition of the coke, the steam is broken up and combines with a portion of the coke, the remainder of which is carried on by the gases in the form of lamp black. The pipe 72, from which the steam jets issue, is so located and protected by the fire brick as to offer no resistance to the flow of gas from the point of combustion toward the discharge flue, owing to the location of the pipe 72 and the condition of the gases when they reach the steam jets. These jets have no effect upon the temperature of the dissociating zone, and are so placed that the steam is decomposed without materially cooling the temperature of the generator. In this connection, it might be pointed out that the office of the flue 94 and pipe 96 is not to extinguish the burning gases, since

70

all of the combustion desired is complete and the gases are extinguished before they reach the flue 94. The function performed by the flue 94 is to hold the products of semi-combustion and the dissociated fuel in a zone of high temperature, mingling them with products of decomposed steam until further re-combination has taken place to a certain extent; the return bend 95 and the pipe 96 5 perform the double function of carrying away the gases to a suitable receptacle and of further enriching the gases. It has also been found that a layer of lamp black is deposited upon the inside of the flue 94 and 10 more or less into the pipe 96, which layer of lamp black is in an incandescent condition and readily combines with hydrogen coming in contact with it, which hydrogen may result from the breaking up of the 15 steam admitted from the pipe 72, the result of the combination being to produce gas of a hydrocarbon form. A further action taking place in the combining flue 94, return bend 95 and outlet pipe 96 may be described 20 as follows: On account of the combination of the air with a portion of the fuel as the air enters the generator, a considerable quantity of carbon dioxid is produced as a result of the complete combustion of that particular portion of the fuel. This carbon dioxid passes through the generator and into the combining flue 94, in which, due to the 25 very high temperature and the presence of carbon in an incandescent condition on the inner wall of the combining flue, and also 30 in suspension in the flue, the carbon dioxid unites with a portion of this carbon, with the result that one molecule of carbon dioxid is broken up, and by the addition of 35 the carbon transformed into two molecules of carbon monoxid. If the steam were admitted 40 at any other place than what might be called the tip of the flame, the result would be to cut down the critical temperature of the combustion at the instant of dissociation 45 and also to prevent the action of the broken-up steam upon the coke deposited on the rear wall.

The heater 65 is so located in front of the 50 opening 8 as to protect the same from the direct action of the flame and the heating surface of this heater is so proportioned as to deliver just the amount of steam from the jets 73 that is required to properly enrich the gas produced at that time by the 55 generator. When less gas is required owing to the filling of the gas holder 55 and the opening of the relief valve 52 the temperature in the chamber 1 is reduced and the 60 amount of steam produced is also reduced and in the right proportion to maintain the quality of the gas practically constant.

In the operation of the generator it has 65 been found desirable to maintain the temperature and viscosity of the oil constant in

order that the difference in pressure between the air main 3 and the inside of the chamber 1 may properly regulate and vary the amount of oil delivered through the opening 8 on to the inclined plane 6. This is accomplished by providing a water jacket for one or both of the receptacles 10 and 103, either hot or cold water being supplied to such water jacket as required by suitable means to be described in order to maintain practically constant viscosity of the oil that the effect of different air pressures upon the oil may always maintain a corresponding ratio of oil delivered through the opening 8 to the amount of air supplied to the chamber 1. The level of the lower flat wall of the outlet opening 8 is just slightly above the weir edge 9, as a result of which when the pressures in the chamber 1 and the air main 3 are equal, the level of the oil in the receptacle 10 will be the same as the level of the oil in the receptacle 103. These receptacles are so designed that for any given difference in air pressure between the air main 3 and the inside of the chamber 1 and for a given adjustment of valve 14 an amount of oil will be supplied through the conduit 13 and through the opening 8 to the inclined plane 6 that will bear a certain ratio to the amount of air entering the chamber 1 95 through the opening 7 for this condition, which ratio will remain practically constant for varying amounts of air supplied to the chamber 1.

The means just described for regulating the fuel supply is very sensitive and permits wide and rapid variations in the quantity of gas produced without any perceptible change in the quality of such gas. It has been found, however, that the amount of friction experienced by the oil in going through the various passages and through the opening 8 does not vary in directly the same ratio that the quantity of oil delivered does, and, further, that the variation in velocity of the air in the air main causes a variation in pressure in the receptacle 10, as a result of which it has been found desirable to use means as shown at 105 for adjusting the air pressure in the receptacle 105 110 relatively to the air pressure in the main 3.

The adjusting means 105 consists in a tube extending into the main 3 below the orifice 5 and having a curved inner end, as a result of which by turning the tube 105 the velocity of the air in the main 3 may be made more or less of a factor in determining the pressure in the receptacle 10. The tube 105 may be adjusted by means of 120 handle 106 and the air pressure is communicated from such tube through openings 107 into the hollow casing 108 and there-through into pipe 11 and thence into the receptacle 10. In this way inequalities due 125 130 135 140 145 150 155 160 165 170 175 180 185 190

either to variation in air velocity or resistance of the various oil passages may be compensated for. It has also been found that it is desirable to make the lower surface of the opening 8 flat and of considerable width relatively in order to maintain practically constant the ratio of the oil supplied to the inclined plane 6 relatively to the amount of air admitted to the chamber 1 from the main 3.

The means employed to control the supply of water to the water jacket 24, 25 surrounding the receptacles 10 and 103 is a thermostat 35, as shown in Figs. 5 to 9, inclusive, supported in the oil in one of the receptacles, as in the receptacle 10, from a bracket 44 projecting from the top of such receptacle. The thermostat 35 consists of two metals of dissimilar expansion coefficients riveted together, as a result of which for variations in temperature the free end will move in one direction or the other, and this movement is caused to make contact between such free end and the contacts 36 and 36^a supported by an insulating block 47 from the top 45 of the receptacle. The contacts 36, 36^a are connected to binding posts 46, 46^a connected through wires 110 and 111 with one terminal of each of the electromagnets 37 and 37^a respectively, the other terminals of which are tied together and connected by wire 112 with battery 113, the other terminal of which battery is connected by wire 114 with the casing of the receptacle 10. The electromagnets 37, 37^a are so mounted as to attract the armature 48 in one direction or the other and by such attraction to move a bucket 39 carried by the shaft 40 upon which the armature 48 is supported. The bucket 39 is carried in a casing 115 in such a manner that its upper end is beneath the lower end of nozzle 31 when the bucket is in one position and the lower end of the nozzle 31^a when the bucket is in the opposite position, the intermediate position of the bucket 39 being between these two nozzles. The lower end of the bucket 39 opens into a passageway 116 connected with pipe 42. Nozzles 31 and 31^a are arranged to be supplied with hot and cold water respectively by means of pipes 28 and 29 by valves 30 and 30^a. The hot water supplied by pipe 28 is furnished in the arrangement shown herein by means of a coil 27 surrounding a portion of the flue 94, said coil receiving its supply from the water supply pipe 26. From the construction described it will be seen that when the valves 30 and 30^a are open water will be supplied to the nozzles 31 and 31^a and there will always be water from one or both of these nozzles delivered into the casing 115 outside of the bucket 39. This water is carried away through an outlet pipe 33 and into a suitable discharge hopper 34. Connection is made from pipe

42 to the water jacket 24 through which water passes under the oil in receptacle 10, thence through an opening formed in the casting into the water jacket 25 formed around the receptacle 103, from which the water is delivered through outlet pipe 43 into the discharge hopper 34. From this it will be seen that when the temperature of the oil in the receptacle 10 becomes too low the thermostat 35 is operated in one direction, thereby operating one of the electromagnets and the bucket 39 is swung into a position to supply hot water to the water jackets 24 and 25, the result being that the temperature of the oil is increased. When the oil has increased sufficiently in temperature the thermostat interrupts the circuit and the bucket 39 resumes its normal or middle position due to the weight of the armature 48. If for any reason the temperature of the oil is increased above the proper point, the thermostat operates in the opposite direction and actuates the other electromagnet, thereby swinging the armature and the bucket to a position to supply cold water to the jackets 24 and 25, thereby cooling the oil until the desired temperature is reached, for which condition the thermostat opens the circuit and the bucket 39 and armature 48 return to normal position. The results secured by this regulation are very important, since a variation in temperature of one-half a degree Fahrenheit causes a perceptible change, and a variation of one degree causes a serious change in the quality of the gas produced.

In order to stop the operation of the generator the handle 16 is moved to the position indicated in dotted lines in Fig. 2 and the valve 14 is closed by means of the spring 17 which prevents further flow of oil from the receptacle 103 into the chamber 1 and thus the production of gas is interrupted.

In my invention I find it desirable to employ an adjustable orifice 5, as shown in Fig. 10. This consists in two superposed plates each having an elliptical opening therein, the lower one, 117, fixed, and the upper one, 118, adjustable relatively thereto. The elliptical openings in the two plates are equal and so disposed that their major axes coincide and are in the line of adjustment of the upper plate, as a result of which when the orifice is adjusted for full opening it is equal to the opening in either plate and as the orifice is contracted in size by the adjustment of the upper plate an opening is maintained of more or less circular form for considerable variations in the area of the orifice, which is desirable in order that the law governing the flow of gases through circular openings may hold practically true for all ranges of adjustment necessary. The upper plate 118 is provided with lugs 119 and 120 for limiting its motion in either

direction, and an adjustable stop 121 is provided for the lug 120 in order that the orifice 5 may be adjusted to its minimum size when desired, as for starting the generator, and then returned to a previous desired setting without special adjustment after the generator has started. This position may be determined by the output required of the generator or for the particular conditions under which the generator is working, for which conditions the working size of orifice 5 is constant. When it is desired to adjust the generator for a different maximum output, as long as this is within the capacity of the generator, the orifice 5 may be given a corresponding adjustment so that when wide open just the amount of air is admitted that is required to produce the maximum quantity of gas for that generator adjustment.

In order to facilitate inspection or repair of the inner part of the generator a removable brick 81 is provided in the rear wall which may be removed by removing the plate 83 from the back of the generator. In addition to this a sight opening 122 is provided in the front of the generator through which a view of the lower edge of the inclined plane may be had, which is very desirable at times to determine whether the oil fed to the generator is of the proper amount. This sight opening 122 is arranged to be opened or closed by means of a swinging gate 123.

As shown in Fig. 11, I find it desirable in some instances to use a modified form of inclined plane 6^a, in which the oil is supplied through a plurality of openings 8^a instead of one continuous opening, as in the construction shown in Fig. 2. I also find it desirable in some cases to form the lower edge of the inclined plane 6^a irregular as indicated in Fig. 11, by which construction I secure a larger area of contact between the air and the oil film and thus facilitate the carrying of the oil particles by the air into the combustion zone. In cases where it is desirable to use the form of lower edge of inclined plane shown in Fig. 11, this edge should occupy such a position relatively to the top of the casting 90 that the total air opening between the inclined plane and the top of the casting is the same as in the modification shown in Fig. 2.

While I have shown my invention in the embodiment herein described, I do not limit myself to this construction, but desire to claim broadly any equivalent means for accomplishing the same results.

What I claim is:

1. In a gas generator, a chamber for producing the gas, means for supplying liquid fuel to such chamber, and means for directing air under pressure to such chamber, such fuel supplying means so constructed as to

regulate the quantity of fuel supplied to such chamber by the direct action of the pressure in such chamber upon the fuel.

2. In a gas generator, a chamber for producing the gas, means for supplying liquid fuel to such chamber, and means for directing air under pressure into such chamber, such fuel supplying means so constructed as to control the quantity of fuel supplied to such chamber by the action upon such fuel of the difference in pressure between the air supplied and the inside of such chamber.

3. In a gas generator, a chamber for producing the gas, means for supplying liquid fuel to such chamber, means for directing air under pressure into such chamber, means for varying the pressure in the chamber relatively to the pressure of the air supply for variations in the quantity of gas produced, and means for regulating the pressure in the chamber relatively to the pressure of the air supply for a constant rate of gas production.

4. In a gas generator, a chamber for producing the gas, means for supplying liquid fuel to such chamber, a main for directing air under pressure into such chamber, and an adjustable orifice in such main, such orifice constituting means for varying the pressure in the chamber relatively to the pressure in the air main for variations in the quantity of gas produced, such orifice also constituting means for regulating the pressure in the chamber relatively to the pressure in the air main for a constant rate of gas production.

5. In a gas generator, a chamber for producing the gas, means for supplying liquid fuel to such chamber, and thermostatic controlling means for maintaining practically constant the temperature of the fuel supplied to such chamber.

6. In a gas generator, a chamber for producing the gas, means for supplying liquid fuel to such chamber, means for directing air under pressure into such chamber, a flue for receiving the dissociated gases from the chamber, and means controlled by the temperature of the chamber for supplying water vapor to the generator in proportion to the temperature of such chamber.

7. In a gas generator, a chamber for producing the gas, means for supplying liquid fuel to such chamber, means for directing air under pressure into such chamber, and a vertical flue adapted to receive, combine and fix the dissociated gases, such flue extending first upward and then downward to a suitable receptacle.

8. In a gas generator, a chamber for producing the gas, means for supplying liquid fuel to such chamber, means for directing air under pressure into such chamber, means for regulating the quantity of fuel supplied to such chamber by the direct action of the

pressure in such chamber upon such fuel, and means for regulating the pressure in the chamber relatively to the pressure of the air supply for a constant rate of gas production.

9. In a gas generator, a chamber for producing the gas, means for supplying liquid fuel to such chamber, means for directing air under pressure into such chamber, means **10** for regulating the pressure in the chamber relatively to the pressure of the air supply for a constant rate of gas production, and means for maintaining practically constant the temperature of the fuel supplied to such **15** chamber.

10. In a gas generator, a chamber for producing the gas, means for supplying liquid fuel to such chamber, means for directing air under pressure into such chamber, means **20** for regulating the quantity of fuel supplied to such chamber by the direct action of the pressure in such chamber upon such fuel, means for regulating the pressure in the chamber relatively to the pressure of the air **25** supply for a constant rate of gas production, and means for maintaining practically constant the temperature of the fuel supplied to such chamber.

11. In a gas generator, a chamber for producing the gas, means for supplying liquid fuel to such chamber, means for directing air under pressure into such chamber, means for regulating the quantity of fuel supplied to such chamber by the direct action of the **30** pressure in such chamber upon such fuel, means for regulating the pressure in the chamber relatively to the pressure of the air supply for a constant rate of gas production, means for maintaining practically constant **35** the temperature of the fuel supplied to such chamber, a flue for receiving dissociated gases from the chamber, and means for adding water vapor to such gases after dissociation.

45 12. In a gas generator, a chamber for producing the gas, means for supplying liquid fuel to such chamber, a main for directing air under pressure into such chamber, an adjustable orifice in such main, such orifice **50** constituting means for regulating the pressure in the chamber relatively to the pressure in the air main for a constant rate of gas production, and means for controlling the quantity of fuel supplied to such chamber **55** by the direct action upon such fuel of the difference in pressure between the air-supply pipe and the inside of such chamber.

13. In a gas generator, a chamber for producing the gas, means for supplying liquid **60** fuel to such chamber, a main for directing air under pressure into such chamber, an adjustable orifice in such main, such orifice constituting means for regulating the pressure in the chamber relatively to the pressure in the air main for a constant rate of **65**

gas production, and means for maintaining practically constant the viscosity of the fuel supplied to such chamber.

14. In a gas generator, a chamber for producing the gas, means for supplying liquid fuel to such chamber, a main for directing air under pressure into such chamber, an adjustable orifice in such main, such orifice constituting means for regulating the pressure in the chamber relatively to the pressure in the air main for a constant rate of gas production, means for controlling the quantity of fuel supplied to such chamber by the direct action upon such fuel of the difference in pressure between the air main and the inside of such chamber, and means for maintaining practically constant the viscosity of the fuel supplied to such chamber. **70** **75** **80**

15. In a gas generator, a chamber for producing the gas, means for supplying liquid fuel to such chamber, a main for directing air under pressure into such chamber, an adjustable orifice in such main, such orifice constituting means for regulating the pressure in the chamber relatively to the pressure in the air main for a constant rate of gas production, means for controlling the quantity of fuel supplied to such chamber by the direct action upon such fuel of the difference in pressure between the air main and the inside of such chamber, a flue for receiving the dissociated gases from the chamber, and means for adding steam to such gases after dissociation. **85** **90**

16. In a gas generator, a chamber for producing the gas, means for supplying oil to such chamber, a main for supplying air under pressure to such chamber, means in such main for restricting the flow of air into such chamber and thereby maintaining the pressure in the main higher than the pressure in the chamber when air is being supplied thereto, and means for regulating the quantity of oil supplied to such chamber by the direct action of the pressure in such chamber upon such oil. **100**

17. In a gas generator, a chamber for producing gas, means for supplying oil to such chamber, a main for supplying air under pressure to such chamber, means in such main for restricting the flow of air into such chamber and thereby maintaining the pressure in the main higher than the pressure in the chamber when air is being supplied thereto, and means for controlling the quantity of oil supplied to such chamber by the direct action upon such oil of the difference in pressure between the air supply main and the inside of such chamber. **115** **120**

18. In a gas generator, a chamber for producing the gas, a first inclosed oil receptacle opening into such chamber, a second inclosed oil receptacle connected with a suitable oil supply pipe, a conduit between the receptacles for supplying oil from such sec- **125** **130**

ond receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main.

19. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main for different velocities of air flow in the air main at the same pressure.

20. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for varying the pressure in such second receptacle relatively to the pressure in the air main for different velocities of air flow in the main.

21. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main.

to the pressure in the air main, and means for maintaining the oil in such second receptacle at practically constant temperature.

22. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, means for maintaining a pressure in such second receptacle equal to the pressure in the air main, and means for maintaining the rate of flow from such first receptacle into the chamber practically constant for the same difference of pressure between the two receptacles.

23. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, means for maintaining the pressure in such second receptacle equal to the pressure in the air main, and means for maintaining the rate of flow from such first receptacle into the chamber practically constant for the same difference of pressure between the two receptacles, such difference in pressure between the two receptacles operating to cause a flow of oil from the first receptacle into the chamber.

24. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, means for maintaining the pressure in such second receptacle equal to the pressure in the air main, and

means for maintaining the rate of flow from such first receptacle into the chamber practically constant for the same difference of pressure between the two receptacles, such difference in pressure between the two receptacles operating to cause a flow of oil from the first receptacle into the chamber proportional to such difference in pressure.

25. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main, the pressure in the second receptacle operating for a lesser pressure in the first receptacle to cause the flow of oil from the first receptacle into the chamber.

30. 26. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main, the pressure in the second receptacle operating for a lesser pressure in the first receptacle to cause the flow of oil from the first receptacle into the chamber and from the second receptacle to the first receptacle.

35. 27. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically

40. cle, means for directing air under pressure into such chamber, means for maintaining the pressure in such second receptacle equal to the pressure in the air main, and means for maintaining the rate of flow from such first receptacle into the chamber practically constant for the same difference of pressure between the two receptacles, such difference in pressure between the two receptacles operating to cause a flow of oil from the first receptacle into the chamber, whereby the ratio of the quantity of oil supplied to the chamber relatively to the amount of air supplied to the chamber is maintained practically constant.

45. 28. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, and means for maintaining the pressure in such second receptacle equal to the pressure in the air main, the pressure in the second receptacle operating for a lesser pressure in the first receptacle to cause the flow of oil from the first receptacle into the chamber, whereby the ratio of the quantity of oil supplied to the chamber relatively to the amount of air supplied to the chamber is maintained practically constant.

50. 29. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such chamber and to maintain the pressure in such first receptacle equal to the pressure in the chamber, means for maintaining a practically constant depth of oil in the second receptacle, means for directing air under pressure into such chamber, means for maintaining the pressure in such second receptacle equal to the pressure in the air main, and a thermostat in the oil in such receptacles for maintaining the temperature of the oil practically constant.

55. 30. In a gas generator, a chamber for producing the gas, a first inclosed oil receptacle opening into such chamber, a second inclosed oil receptacle connected with a suitable oil supply pipe, a conduit between the

receptacles for supplying oil from such second receptacle to such first receptacle, the opening between such first receptacle and the chamber adapted to supply oil to such 5 chamber and to maintain the pressure in such first receptacle equal to the pressure in the chamber, means for maintaining a practically constant depth of oil in the second receptacle, means for directing air under 10 pressure into such chamber, means for maintaining the pressure in such second receptacle equal to the pressure in the air main, a water jacket associated with one of such receptacles, and a thermostat in the oil contained in such receptacles, such thermostat serving to maintain practically constant the 15 temperature of the water in the water jacket.

31. In a gas generator, a chamber for producing the gas, a first inclosed oil receptacle 20 opening into such chamber, a second inclosed oil receptacle connected with a suitable oil supply pipe, a conduit between the receptacles for supplying oil from such second receptacle to such first receptacle, the 25 opening between such first receptacle and the chamber adapted to supply oil to such chamber and to maintain the pressure in such first receptacle equal to the pressure in the chamber, means for maintaining a practically 30 constant depth of oil in the second receptacle, means for directing air under pressure into such chamber, means for maintaining the pressure in such second receptacle equal to the pressure in the air main, 35 a water jacket associated with one of such receptacles, mechanism for supplying hot or cold water to such water jacket as desired, and a thermostat in the oil contained in such receptacles, such thermostat serving to operate such mechanism to maintain practically 40 constant the temperature of the water in the water jacket.

32. In a gas generator, a chamber for producing the gas, a first inclosed oil receptacle 45 opening into such chamber, a second inclosed oil receptacle connected with a suitable oil supply pipe, a conduit between the receptacles for supplying oil from such second receptacle to such first receptacle, the opening 50 between such first receptacle and the chamber adapted to supply oil to such chamber and to maintain the pressure in such first receptacle equal to the pressure in the chamber, means for maintaining a practically 55 constant depth of oil in the second receptacle, means for directing air under pressure into such chamber, means for maintaining the pressure in such second receptacle equal to the pressure in the air main, and 60 means for adjusting the relation between the pressures in such receptacles to compensate for the variation in the ratio of flow resistance to quantity of oil supplied to the chamber.

ber, whereby the ratio of such oil to the air supplied to such chamber is maintained 65 practically constant.

33. In a gas generator, a chamber for producing the gas, a first inclosed oil receptacle opening into such chamber, a second inclosed oil receptacle connected with a suitable oil supply pipe, a conduit between the receptacles for supplying oil from such second receptacle to such first receptacle, the opening between such first receptacle and the chamber adapted to supply oil to such 70 chamber and to maintain pressure in such first receptacle equal to the pressure in the chamber, means for maintaining a practically constant depth of oil in the second receptacle, means for directing air under 75 pressure into such chamber, and means for adjusting the relation between the pressures in such second receptacle and the air main to compensate for the variation in the ratio of flow resistance to quantity of oil supplied 80 to the chamber, whereby the ratio of such oil to the air supplied to such chamber is maintained practically constant.

34. In a gas generator, a chamber for producing the gas, a first inclosed oil receptacle 90 opening into such chamber, a second inclosed oil receptacle connected with a suitable oil supply pipe, a conduit between the receptacles for supplying oil from such second receptacle to such first receptacle, the opening 95 between such first receptacle and the chamber adapted to supply oil to such chamber and to maintain the pressure in such first receptacle equal to the pressure in the chamber, means for maintaining a practically 100 constant depth of oil in the second receptacle, means for directing air under pressure into such chamber, means for maintaining the pressure in such second receptacle equal to the pressure in the air main, means for 105 adjusting the relation between the pressures in such receptacles to compensate for the variation in the ratio of flow resistance to quantity of oil supplied to the chamber whereby the ratio of such oil to the air supplied to such chamber is maintained practically 110 constant, and means for adjusting the ratio of such fuel to the air supplied.

35. In a gas generator, a chamber for producing the gas, a first inclosed oil receptacle 115 opening into such chamber, a second inclosed oil receptacle connected with a suitable oil supply pipe, a conduit between the receptacles for supplying oil from such second receptacle to such first receptacle, the 120 opening between such first receptacle and the chamber adapted to supply oil to such chamber and to maintain the pressure in such first receptacle equal to the pressure in the chamber, means for maintaining a practically 125 constant depth of oil in the second receptacle,

cle, means for directing air under pressure into such chamber, means for adjusting the relation between the pressures in such second receptacle and the air main to compensate for the variation in the ratio of flow resistance to quantity of oil supplied to the chamber whereby the ratio of such oil to the air supplied to such chamber is maintained practically constant, and means for adjusting the ratio of such fuel to the air supplied.

36. In a gas generator, a chamber for producing the gas, means for supplying liquid fuel to such chamber, means for directing air into such chamber, and means for containing a vertical column of such fuel in communication with the chamber, such column so contained as to vary in height for variations in pressure in the chamber, variations in the height of such column serving to vary the quantity of fuel supplied to the chamber.

37. In a gas generator, a chamber for producing the gas, means for supplying liquid fuel to such chamber, means for directing air under pressure into such chamber, and means for maintaining practically constant the temperature of the fuel supplied to such chamber.

38. In a gas generator, a chamber for producing the gas, means for supplying liquid fuel to such chamber, and a thermostat in such fuel for maintaining practically constant the viscosity of the fuel supplied to such chamber.

39. In a gas generator, a chamber for producing the gas, means for supplying liquid fuel to such chamber, a water-jacketed receptacle for such fuel, and means for maintaining practically constant the temperature of the water in such water jacket.

40. In a gas generator, a chamber for producing the gas, means for supplying liquid fuel to such chamber, a water-jacketed receptacle for such fuel, and a thermostat in such fuel for maintaining practically constant the temperature of the water in such water jacket.

41. In a gas generator, a chamber for producing gas from liquid fuel, and means for so maintaining a column of fuel in communication with the chamber that variations in

the pressure in the chamber produce variations in the height of such column.

42. In a gas generator, a chamber for producing gas from liquid fuel, means for so maintaining a column of fuel in communication with the chamber that variations in the pressure in the chamber produce variations in the height of such column, and means for supplying fuel from such column to the chamber in quantities proportional to the height of the column.

43. In a gas generator, a chamber for producing gas from liquid fuel, a receptacle for containing the liquid fuel, such receptacle having a delivery opening leading therefrom to the chamber, such receptacle and delivery opening so disposed that variations in pressure in the chamber produce corresponding variations in the quantity of fuel delivered through such opening.

44. In a gas generator, a chamber for producing gas from liquid fuel, a receptacle for containing the liquid fuel, such receptacle having a delivery opening leading therefrom to the chamber adapted to subject the surface of the liquid in the receptacle to the pressure in the chamber, such receptacle and delivery opening so disposed that variations in pressure in the chamber produce corresponding variations in the quantity of fuel delivered through such opening.

45. In a gas generator, the combination of a chamber for producing the gas, a liquid fuel receptacle associated with the wall of the chamber, and an open passage from the chamber to the top of the receptacle.

46. In a gas generator, a chamber for producing the gas, means for supplying liquid fuel to such chamber, and means of the wall of the chamber for containing a vertical column of such fuel in communication with the chamber, such column so contained as to vary in height for variations in pressure in the chamber.

In witness whereof, I hereunto subscribe my name this 10th day of April, A. D. 1908.

ORVILLE H. ENSIGN.
